UNITED STATES PATENT OFFICE.

FRANCIS P. FRENCH, OF DENVER, COLORADO.

CARPET-LINING.

SPECIFICATION forming part of Letters Patent No. 269,039, dated December 12, 1882.

Application filed June 1, 1882. (No model.)

To all whom it may concern:

Be it known that I, FRANCIS P. FRENCH, of Denver, in the county of Arapahoe, and in the State of Colorado, have invented an Improvement in Carpet-Linings; and I do hereby declare that the following is a full, clear, and exact description thereof.

My invention relates to paper linings for carpets; and it consists in certain peculiarities of construction, all as more particularly set forth hereinafter.

In the drawings, Figure 1 is a perspective view of a portion of one of my improved carpet-linings. Fig. 2 is a section of the same. Figs. 15 3 and 4 are perspective views of modified forms of my said linings. All of these views represent the linings upside down, or the reverse from their position when in use, the better to illustrate their construction.

20 A represent sections of the carpet-lining, made of paper or analogous material, and preferably molded into the shapes shown directly from the pulp.

25 a a are small holes or perforations (which may be round, square, oblong, or of diamond or any other shape preferred) to admit the dust from the carpet through to the under side of the lining.

30 b b represent the thickest portions of my lining, while c c designate the spaces between these thick portions on the under side of the lining, which spaces are produced by making the lining of only about half the thickness at these places that it is at b b. This, as intimated, can be most easily effected by molding the lining entire directly from the paper-pulp; but it is obvious that a similar effect may be accomplished by making the portions b b separately and afterward securing them to the 35 under side of the main body of the carpet-lining either by glue or other adhesive substance or by stitching them to place, or by tacks, pins, rivets, or other well-known means of attachment; but I prefer to have my lining all in 40 one solid piece, as it can thus be more cheaply made, besides being neater in appearance and more durable than when made in many pieces and afterward united together.

45 The spaces c between the portions b may be 50 of any desired width, from the narrow grooves

shown in Figs. 1 and 2 to the wide channels shown in Fig. 3, and the said spaces may be either in straight lines, as in the figures just named, or may be, as shown in Fig. 4, irregular in outline and dependent upon the shape of 55 the portions b, which may be circular, as here represented, or square, oblong, lozenge-shaped, &c., as desired.

When the lining is in place its upper side will present a smooth surface (perforated at 60 intervals) for the reception of the carpet. The dust in the latter, instead of settling between the lining and the carpet, as with the old solid linings, will sift through the described perforations and lodge in the spaces c between the 65 floor and lining, while the walls of the thick portions b will keep it in place and prevent its rising again when the carpet is next swept, besides which, by reason of its final lodgment in the described spaces, all unevenness of the 70 lining is prevented, as might otherwise occur, if the lining were simply perforated, without the spaces c, which unevenness has been an objection to perforated carpet-linings hitherto used. My lining thus not only, by its perfect 75 evenness, prevents undue wear of the carpet, but also enables a carpet to be swept without raising clouds of dust, which is the great objection to carpets laid upon the ordinary linings now in use.

80 Having thus described my invention, what I claim as new, and desire to secure by Letters Patent, is—

A carpet-lining having a body of unequal thickness and presenting a smooth upper surface, provided with perforations at intervals for the transmission of dust, the thinner portions of the lining forming spaces on the under side for the reception and retention of the dust transmitted through the described perforations, and the thicker portions being solid or integral with the body of the said lining, as set forth.

85 In testimony that I claim the foregoing I have hereunto set my hand this 10th day of 90 March, 1882.

FRANCIS P. FRENCH.
